UNITED STATES PATENT OFFICE.

RAYMOND G. MOORE, OF BRIDGEPORT, CONNECTICUT, ASSIGNOR TO THE BASSICK COMPANY, OF BRIDGEPORT, CONNECTICUT, A CORPORATION OF CONNECTICUT.

HOOD CATCH.

Application filed February 14, 1924. Serial No. 692,633.

This invention relates to an improved automobile hood catch, and has for an object to provide a device of this character which may be operated with facility, and will effectually secure the hood in closed position without looseness or rattling.

Another object is to provide a catch which, in its clamping action, will exert both a downward and a lateral inward pressure upon the hood, thereby securely holding the upper portion of the hood down tightly upon the hood supporting structure of the body, and firmly pressing the hinged sides inwardly against the abutment portions of the frame.

A further object is to provide a catch including an improved leverage arrangement for producing by a single directional force a plurality of pressure components adapted 20 to act upon the hood to force it downwardly and inwardly.

Still further objects are simplicity of construction, ease of operation, and freedom from parts which will readily wear or get 25 out of order.

With the above and other objects in view, embodiments of my invention are shown in the accompanying drawings, and these embodiments will be hereinafter more fully described with reference thereto, and the invention will be finally pointed out in the claims.

In the drawings:

Fig. 1 is a side elevation of a hood catch, 35 according to the present embodiment of the invention, and showing the same attached to an automobile hood and frame;

Fig. 2 is a front elevation of the same;

Fig. 3 is a side elevation, and showing 40 the catch unhooked from the hood;

Fig. 4 is a sectional plan view taken along the line 4-4 of Fig. 3;

Fig. 5 is a side view of a modified form 45 of resilient bumper adapted to be employed;

Fig. 6 is a side view of another modified bumper in the form of a roll; and

Fig. 7 is a front view thereof.

Similar reference characters indicate 50 corresponding parts throughout the several figures of the drawings.

Referring to the drawings, the hood catch, according to the present embodiment of the invention, consists of a cylindrical barrel 10, flanged at its lower end, as at 11, to provide 55 a reduced passage in which a rod 12 is

slidably engaged, the end of the rod within the barrel being provided with a head 13 between which and the flange 11 a spring 14 is coiled about the rod.

The upper end of the barrel is threaded, as 60 at 15, and is screwed into the threaded socket 16 of a cap member 17, which closes the upper end of the barrel and forms a stop to limit the upward movement of the rod 12 under the pressure of the spring. A 65 clamping hook 18 and a handle 19 are formed integrally with the cap member.

At its lower end the rod 12 is provided with an eye 20, and is pivotally connected to a pair of links 21 and 22 by means of 70 a riveted pin 23 engaged in holes in the outer ends of the links and passing through the eye 20, said links being pivotally connected at their other ends to a bracket 24 by means of a riveted pin 25 engaging 75 aligned holes in the bracket and in the inner ends of the links. The bracket is preferably formed of sheet metal having a central upwardly extending inverted U-shape portion and base portions extending outwardly 80 therefrom, and which are secured to the automobile frame 26 by bolts 27.

The automobile hood 28, which in its closed position is engaged against a stop flange 29 secured to the frame is essentially 85 provided with a keeper for engagement of the hook 18 to draw it downwardly toward the frame under the pressure of the spring 14, and between the barrel and hood there is provided a bumper or stop, preferably 90 resilient, which cooperates between them under the leverage action of the linked connection of the rod 12 with the bracket 24 to force the hood laterally inward against the flange 29.

In the present embodiment of the invention these elements form part of a single device which is attached to the outer side of the hood, and which comprises a base plate 30 secured by rivets 31 to the hood, 100 and having a pocket-like keeper 32 pressed outwardly therefrom, the projected surface of which is inclined from the relatively wide open top to the base plate and is provided with a stop lug 33 struck inwardly at right 105 angles to said inclined surface and spaced downwardly from the upper forward hook engaging edge. When the hook is engaged with the keeper the inclined surface cams the hook inwardly and upon engagement 110

with the stop lug forces the hood downwardly.

Below the keeper portion the base plate is offset from the hood surface, as at 34, the lower extremity of the base being bent inwardly, as at 35, into engagement with the hood, to thereby distribute the inward pressure upon said offset portion and prevent buckling of the hood.

10 A resilient bumper block 36 is secured upon the offset portion 34 by means of a plate 37 having its side edges clamped about the sides of said offset portion, and provided at its upper and lower edges with prongs 38 and 39 which are embedded into the block to thereby securely clamp the same in place.

The operation is as follows, Figs. 1 and 2 showing the operative or engaged position of the catch, and Fig. 3 the inoperative or 20 disengaged position. As shown in Fig. 3 the catch is contracted and the links 21 and 22 are swung to a substantially horizontal position with the lower end of the rod 12 at its maximum distance from the hood. In order 25 to engage the catch the same is pulled upwardly by means of the handle 19 against the pressure of the spring 14 to a point permitting engagement of the hook 18 with the keeper. At the same time the links are 30 swung upwardly, decreasing the distance between their outer ends and the hood and moving the barrel laterally inward against the bumper block, thereby forcing the hood inwardly tightly against the flange 28. As

35 the hook moves downwardly into place under the pressure of the spring, forcing the hood downwardly, the links are further swung upwardly and inwardly through the contraction of the rod into the barrel, thereby tightly pressing the barrel against the bumper. This action is furthered by the camming action of the inclined keeper which 40 forces the latch inwardly at the same time as it moves downwardly. Thus the one directional force of the spring is distributed into components exerting both a downward and an inward force or pressure upon the hood to securely clamp it in closed position.

In Fig. 5 I have illustrated a modified 50 form of resilient bumper block 40 attached directly to the hood independently of the keeper, which latter may be of any suitable form. The block 40 is set into a flanged base 41, and is secured to the hood by means 55 of a rivet 42 having an enlarged retaining head 43 disposed within a shouldered passage 44 of the block. It will be understood that the bumper block may be of any desirable shape or material, and may be attached in any suitable manner. The material preferably employed is rubber.

In Figs. 6 and 7 I have illustrated a further modified form of bumper comprising a metal roller 45 mounted upon a spindle 60 supported in ears 47 and 48 bent from

the offset portion 34 of the keeper base plate, the side of the barrel adapted to engage and press inwardly upon the roller as the catch is hooked with the keeper. The roller may obviously be mounted upon the 70 hood in any suitable manner.

I have illustrated preferred and satisfactory embodiments of the invention, but it will be obvious that changes may be made therein, within the spirit and scope thereof, 75 as defined in the appended claims.

Having thus described my invention, what I claim and desire to secure by Letters Patent is:

1. In a hood catch, or the like, a hold 80 down clamp, a keeper adapted to be engaged by said clamp, a securing base for said clamp, spring means adapted to yieldingly engage said clamp with said keeper and exerting a downward pressure thereon, movable connection means between said base and clamp relatively movable with respect to said clamp and adapted to move said clamp laterally under the action of said spring means, and a stop between the hood 90 and said clamp fixed relatively to one of them, and adapted by engagement with the other to limit the lateral movement of said clamp under the action of said spring and movable connection. 95

2. In a hood catch, or the like, a hold 100 down clamp, a keeper adapted to be engaged by said clamp, a securing base for said clamp, spring means adapted to yieldingly engage said clamp with said keeper and exerting a downward pressure thereon, movable connection means between said base and clamp relatively movable with respect to 105 said clamp and adapted to move said clamp laterally under the action of said spring means, and a stop adapted to be secured to the hood and adapted by engagement of said clamp therewith to limit the lateral movement of said clamp under the action of said spring and movable connection. 110

3. In a hood catch, or the like, a hold 115 down clamp, a keeper adapted to be engaged by said clamp, a securing base for said clamp, spring means adapted to yieldingly engage said clamp with said keeper and exerting a downward pressure thereon, toggle means between said base and clamp adapted to move said clamp laterally under the action of said spring means, and a stop between the hood and said clamp fixed relatively to one of them, and adapted by engagement with the other to limit the lateral movement of said clamp under the action of said spring and said toggle means. 120

4. In a hood catch, or the like, a hold 125 down clamp, a keeper adapted to be engaged by said clamp, a securing base for said clamp, spring means adapted to yieldingly engage said clamp with said keeper and exerting a downward pressure thereon, 130

- a link pivotally connected and interposed between said base and said clamp adapted to move said clamp laterally under the action of said spring means, and a stop between the hood and said clamp fixed relatively to one of them, and adapted by engagement with the other to limit the lateral movement of said clamp under the action of said spring and said link.
- 5 10 5. In a hood catch, or the like, a hold down clamp, a keeper adapted to be engaged by said clamp and having a downwardly and inwardly inclined surface, a securing base for said clamp, spring means adapted to yieldingly engage said clamp with said keeper and exerting a downward pressure thereon, a link pivotally connected and in-

terposed between said base and said clamp adapted to move said clamp laterally under the action of said spring means, and a stop 20 between the hood and said clamp fixed relatively to one of them, and adapted by engagement with the other to limit the lateral movement of said clamp under the action of said spring and said link, said inclined 25 surface of said keeper and said link adapted to move said clamp inwardly in substantially equal relation whereby a substantially parallel relation of said clamp is maintained during compression relation with said stop.

Signed at Bridgeport, county of Fairfield, and State of Connecticut, this 12th day of February, 1924.

RAYMOND G. MOORE.
